UNITED STATES PATENT OFFICE

SIDNEY C. VINCENT, OF BALTIMORE, MARYLAND

ELECTRIC TIME SWITCH

Application filed June 19, 1924. Serial No. 721,025.

This invention relates to electric time switches, or those switches that are automatically operated by a time or clock mechanism for closing and opening electric circuits.

Electric switches of this character have objections which I seek to overcome, and the primary object of this invention is to provide a mechanism in which the driving means for the time or clock mechanism is relieved of the work of opening and closing the switch, that is to say, a mechanism in which the time mechanism is utilized only to actuate certain devices or elements to put into operation the switch opening and closing means, and to provide a novel, simple, durable and compact mechanism for this purpose.

A still further object of the invention is to provide a mechanism by which the movement from the two extreme positions of the switch (opening or closing) will be instantaneous, thereby preventing arcing with its consequent disadvantages.

A still further object of the invention is to provide a construction in which certain parts of the mechanism may be readily disconnected to enable the switch to be operated manually should anything go wrong with the mechanism for automatically operating it.

In the drawings illustrating the invention—

Fig. 1 is a plan view of the switch.

Fig. 2 is a similar view with the dial of the clock mechanism and the parts carried thereby removed.

Fig. 3 is a side elevation.

Fig. 4 is a section taken about on the lines 4—4 of Fig. 1.

Figs. 5 and 6 are views showing different positions of the tripping lever.

Fig. 7 is a plan view of the mechanism, both clock and switch, with the top plate removed.

Fig. 8 is an elevation and partial section of the switch operating mechanism proper, the clock dial and parts carried thereby being omitted.

In the mechanism about to be described,

the gear trains, springs, etc. are mainly carried between two plates, a top plate 1, and bottom plate 2, and in the present instance, the bottom plate is firmly secured to a block 3 by screws 4, the block being preferably wholly or in essential parts, of insulating material. The plates 1 and 2 are secured together and spaced apart by the usual posts 5, and are shaped to accommodate and form bearings for the various shafts upon which are mounted the various gear wheels and pinions of both the clock mechanism and the switch mechanism, and their inter-dependent elements.

The escapement device which may be referred to as a whole, and which is designated by the numeral 6, is of well known construction, and need not be referred to in detail. The numeral 7 designates the spring barrel mounted upon the main or arbor shaft 8. This shaft is journaled in suitable bearings in the plates 1 and 2, and the spring barrel is provided with a gear 9 which meshes with a pinion 10 on shaft 11 below the plate 1, the shaft being journaled in the upper and lower plates. The shaft 11 above the plate is provided with a pinion 12 in mesh with a wheel 13 carried by a sleeve 14. The numeral 15 designates the clock dial provided centrally at its underside with a split sleeve 16 which embraces the sleeve 14 of the wheel 13, upon which sleeve the split sleeve is frictionally held.

Above the dial is a boss 17 which extends through circular apertures in the tripping arms 18. The dial is provided with circular slots 19 and 20, in which travel two similar set screws 21 carried by the tripping arms 18 and arranged for adjustment of said arms at any suitable point upon the dial, the dial being provided with graduations and dividing the day into two periods of twelve hours each. The tripping arms are bevelled in the same direction as indicated at 22. Mounted upon a stub shaft 23 is the tripping lever 24 of the bell crank type. The outer end of this lever is provided with an up-turned engaging portion 25 adapted to be alternately engaged by the bevelled ends of the operating arms 18 to

trip the mechanism to open or close the switch as the exigencies of the case may require. Pivoted to this upstanding portion 25 is a pivoted pointer 26 relative to which, 5 the numerals and graduations upon the dial, the time is indicated. The time for tripping the mechanism, or opening or closing the switch is determined by the position of the tripping arms 18, which arms are moved to 10 the desired numeral, or to the desired graduations between the numerals, and adjusted accurately with its straight edge upon the numeral or graduations when the set screws are tightened, thus insuring the infallible 15 tripping operation at the predetermined time. The outer end of the lever 24 is forced constantly toward the dial by a leaf spring 24' held rigidly in the top plate at its outer end, with its inner end bearing 20 against the edge of the inner arm of the lever 24, as shown in Fig. 2. The inner end of the tripping lever 24 is provided with downwardly extending pin-engaging lug 27 which extends through an elongated slot 28 25 in the top plate, and is adapted to extend into the path of movement of one or the other of two pins 29 and 30 carried on the upper face of a gear wheel 31 mounted upon a shaft 32 journaled in the upper and lower 30 plates 1 and 2.

The shaft 32 carries a pinion 33, in mesh with a wheel 34 on shaft 35 journaled in the plates. This shaft 35 further carries adjacent the lower plate 2 a gear wheel 36 in 35 mesh with a wheel 37 mounted on a sleeve 38 which in turn is mounted on shaft 39. The shaft 39 carries a spring barrel 40 fitted with a wheel 41 in mesh with the pinion 42 mounted on a winding shaft 43 journaled in 40 a bracket 44 on the top plate 1.

The numeral 32^a designates a shaft journaled between the plates and carrying near its upper end, just beneath the top plate, a pinion 32^b Fig. 7 in mesh with pin wheel 31. 45 Near the lower end of this shaft 32^a, just above the bottom plate 2, is a wheel 32^c in mesh with pinion 32^d on the shaft of the butterfly-governor 32^e. The shaft 35 carries above the plate 1, a disk 45 provided at 50 its under face with a downwardly extending pin 46, which is adapted to engage a cam 48 formed in the inner arm of the tripping lever 24 for the purpose, as will be herein-after described, of controlling short rocking 55 movements of the tripping lever to cause the latter to arrest the movement of the wheel 31 in the operation of the mechanism.

The numeral 49 designates a disk provided on the underside with a boss 50 through 60 which and the disk the shaft 39 extends, the disk being secured to the shaft by set screw 51. The disk 49 is provided with a stud 52 adapted for alternate engagement with two downwardly extending lugs 53 and 54 carried by the head 55, the lugs being arranged

in different planes. This head is provided with an extension 56 which with an arm 57 forms a link 58 twisted from flat to vertical position to form an end 59 embraced by the bifurcated end 60 of the switch lever 60', the mode of attachment being by means of a set screw 61, readily removable so as to disconnect the link 58 from the switch, in case anything goes wrong with the clock mechanism, when it is desired to operate the 75 switch by hand.

Reverting to the head 55, this is provided with an elongated slot 62 through which the upper end of the shaft 39 extends for the purpose of guiding the link in a straight 80 line in its movements. The shaft 39 is internally threaded at the top for the reception of a screw 63 between which and the head is preferably interposed a small washer 64.

The switch is of the tumbler variety. The porcelain base 65 thereof is secured to the block 3 by screws 66. In a recess 67 is secured an A-shaped bracket 68, the upwardly extending arms or portions of which are 90 spaced apart for the reception of the switch lever 60', said lever being pivoted at 70 between said arms. The lever comprises a member of insulating material 70^a, and a plate 70^b embedded in said material. To the 95 lower end of the plate is attached the upper end of a pin 71, the lower end of said pin extending through an aperture 72 in the bridge piece 73 of a U-shaped member 74 pivoted at 75 to the arms of the bracket 68. 100

Pivoted at 75^a to the upper end of the member 74, outside of the arms thereof, are the tumblers 76 (of which there are two) of diamond shape, and provided with terminal engaging ends 77, adapted to engage the terminals 78 (of which there are two) and terminals 79 in the bottom of the recess opposite the first mentioned terminals, to close a circuit. Obviously the rocking of the lever in the opposite direction will disengage the tumblers 76 from the terminals and open the circuit. The spring and pin connections between the switch lever and the U-shaped member 74 are for accelerating the movement of the lever and tumblers after the 115 lever has passed the central point, so as to quickly open or close the circuit.

The upper end 80 of the switch lever is provided with a bore 81 which receives the reduced upper end of the insulator portion 120 of the switch lever, making a cap-like connection between the link 58 and the lever, the point 80 being of insulating material.

Operation

As intimated in the introduction, there is no driving connection between the clock mechanism and the switch actuating mechanism, and only such connection exists that at a predetermined time, according to the ad- 130

justment of the tripping arms carried by the clock dial, the tripping lever will be actuated to permit the switch operating spring 40' in the drum 40 to function for a time just sufficient to draw the switch lever 5 slightly past the medial point of its movement when the movement of all of the operative parts between the two mechanisms ceases.

10 Normally the downwardly extending pin 10 engaging lug 27 of the tripping lever is in engagement with the pin 30 on the wheel 31, thus preventing the rotation of the shaft 32, which through pinion 33 and wheel 34, the 15 shaft 35 is rotated at times, by the switch operating spring 40', through the gear wheels 36 and 37 carried respectively on the shafts 35 and 39. When in normal position, the engaging portion 25 of the tripping lever 20 is in the path of movement of the tripping arms 21 and 22. The moving engagement between the bevel end of the arm and the tripping lever, will cause said lever to be rocked slightly, and when the part 25 is 25 about half way of the bevel of the arm, the pin engaging lug 27 on the other end of the lever will release the pin 30, and permit the shaft 32 to make a partial revolution meantime bringing the lug 27 into the path of 30 movement of the pin 29, arresting the movement of the shaft 32. When, caused by the further movement of the arm carried by the dial, the engaging portion 25 passes the highest point of the arm, the leaf spring 24' 35 will force back the tripping lever 24 to the position shown in full lines in Fig. 2 and Fig. 6, in which position the lug 27 is out of the path of movement of both of the pins 29 and 30, thus permitting the shaft 32 to be 40 revolved by the power of the switch operating spring 40', for certain purposes that will appear.

By the engagement of the pins 29 and 30 with the lug 25 of the tripping lever through 45 the gear train between shafts 35 and 39, the switch operating spring has been held out of action. However, when it has been released by the disengagement of the lug 25 from the pins 29 and 30, the spring will be free to 50 act to revolve the shaft 39, and consequently the disk 49 carried by said shaft. The rotation of this disk brings the stud 52 alternately against the lower side of lug 54 to move the switch lever in one direction, and 55 the upper side of lug 53 to move it in the opposite direction. During this movement of the switch lever through the link 58, the link is guided in a straight line by the slot and pin connection shown.

60 When the shaft 35 is rotated through the described train of gearing, it will cause the pin 46 to engage at the proper time, the cam 48 in the inner arm of the tripping lever, to restore the arm to normal position, or the 65 position shown in Fig. 5, in which position

the pin engaging lug 27 is again in engagement with the pin 30 on the wheel 31, the switch being then in position for a reverse operation, as for instance, if the last operation has been to move the switch lever in one direction, the next operation will move 70 it in the other.

It will be noted that the switch employed is of the tumbler variety, to which has been added certain elements in applicant's combination. 75

I claim:

1. The combination with a lever snap switch, of a clockwork mechanism for operating said switch, said clockwork mechanism including a timing device, a switch operating device, primary starting means controlled by the timing device, and operable upon the timing device reaching a predetermined position to release the switch operating device and a secondary device operable upon further movement of the timing mechanism to further release the switch operating device and thereby effect operation of the switch, said switch operating device including a tripping lever having a cam face on one side thereof, and a revolving disk provided with a pin for rocking said lever, said device including a gear engageable by said lever to hold the device from movement. 95

2. In a mechanism of the character described, in combination, a suitable frame, a clock mechanism including a dial having tripping arms adjustably secured thereto, a tripping lever actuated by said arms, a switch operating mechanism including a shaft journaled in the frame, a spring for rotating said shaft at intervals, said spring being independent of the driving spring of the clock mechanism, a shaft journaled in the frame carrying pins adapted to be alternately engaged and released by the tripping lever to hold the switch operating mechanism inactive, or to permit it to operate, a switch including a switch lever, a link connected at one end to the top of the switch lever and provided at the other end with a head having an elongated slot therein adapted to embrace the upper end of the main shaft of the switch operating mechanism for guiding the link in a straight line in either direction, said head being provided with two downwardly extending lugs out of line with each other, a disk mounted on the shaft of the switch operating mechanism and carrying an upwardly extending lug adapted to engage alternately the lugs on said head to operate the switch through the link in either direction. 115

3. In a mechanism of the character described, in combination, a suitable frame, a clock mechanism including a dial having tripping arms adjustably secured thereto, a tripping lever actuated by said arms, a 120

switch operating mechanism including a shaft journaled in the frame, a spring for rotating said shaft at intervals, said spring being independent of the driving spring of the clock mechanism, a shaft journaled in the frame and carrying pins adapted to be alternately engaged and released by the tripping lever to hold the switch operating mechanism inactive, or to permit it to operate, a switch including a switch lever, a link connected at one end to the top of the switch lever, and provided at the other with a head having an elongated slot therein adapted to embrace the upper end of the main shaft of the switch operating mechanism for guiding the link in a straight line in either direction, said head being provided with two downwardly extending lugs out of line with each other, a disk mounted on the shaft of the switch operating mechanism and carrying an upwardly extending lug adapted to engage alternately the lugs on said head to operate the switch through the link in either direction, and means for accelerating the movement of the switch lever after it has passed the center of its movement and thereby accelerate the opening and closing of the switch.

4. In a mechanism of the character described, in combination, a suitable frame, a clock mechanism including a dial having tripping arms adjustably secured thereto, a tripping lever actuated by said arms, one end of said lever being provided with means for engaging the tripping arms and the other end being provided with a downwardly extending engaging portion, a shaft journaled in the frame and having a member provided with pins adapted to be alternately engaged by the downwardly extending engaging portion of the tripping lever to arrest the rotation of said shaft, and to be released by said lever to permit rotation of the shaft, a second shaft carrying at its upper end a pin adapted to engage the tripping lever to rock the same into the path of movement of one of the first mentioned pins, a shaft having a switch operating spring mounted thereon, said spring being held inoperative normally by the engagement between the tripping lever and the engaging pins on the first mentioned shaft, a switch including a switch lever, a disk carried by the main shaft of the switch operating mechanism, connections between said disk and lever whereby when the shaft is rotated the switch lever will be actuated.

In testimony whereof I affix my signature.

60

SIDNEY C. VINCENT.
